UNITED STATES PATENT OFFICE.

MAURICE N. CONNOR, OF BUFFALO, NEW YORK, ASSIGNEE TO FRANK W. CARTER, OF BUFFALO, NEW YORK.

CARBONATED-LIQUOR TANK.

1,235,658.

Specification of Letters Patent.

Patented Aug. 7, 1917.

Application filed June 13, 1913. Serial No. 773,545.

To all whom it may concern:

Be it known that I, MAURICE N. CONNOR, a citizen of the United States, residing at Buffalo, in the county of Erie and State of New York, have invented certain new and useful Improvements in Carbonated-Liquor Tanks, of which the following is a specification.

This invention relates generally to improvements in carbonated liquor tanks and particularly to means for protecting the packing and preventing leakage about the shaft of the agitator, utilized in such tanks.

More specifically the invention relates to an agitator tank structure comprising a tank, having an agitator mounted in suitable bearings therein and adapted to be operated by suitable mechanism extending through the tank and comprising a stuffing box and bearing structure, an operating shaft extending therethrough, a head formed on said operating shaft and having a driving and sliding engagement with the agitator shaft, together with means on the outside of the stuffing box structure for operating the shaft and for moving it endwise to draw the head thereon against the stuffing box and bearing structure to prevent leakage about this shaft.

The invention may be further briefly summarized as consisting in the combination and construction of parts hereinafter set forth in the following description, drawings and claims.

Referring to the drawings, Figure 1 is a vertical section through the tank, showing the valve mechanism and agitator; Fig. 2 is a horizontal section; Fig. 3 is a section through the head looking toward the tank; and Fig. 4 is a section through the tank.

In carrying out the invention any desired tank may be employed so long as it possesses the necessary characteristics, but I have shown one arrangement in the drawings which is effective in operation, and in such embodiment 1 represents the tank provided with a bottom 2 having a bearing 3 at the center thereof for a purpose to be described. The opposite end of the tank is rounded and receives a head connection 4 rigidly secured to the tank in any suitable manner. Secured to this head connection is a suitable head 5 having therein a water inlet and discharge chamber 6, a gas inlet 7 and a gas discharge chamber 8 connected to the head, and communicating with the main

inlet and discharge is a pipe 9 extending into the tank and to a point near the bottom thereof, as shown in Fig. 1. Leading out from the periphery of the head and communicating with this same discharge chamber 6 is a discharge pipe 10. Connected to the gas inlet chamber is a suitable gas delivery pipe 11 adapted to be supplied with carbonic acid gas from any suitable source. This chamber also communicates with the interior of the tank by means of a pipe 12 projecting into the tank and directed downward toward the opposite end. The gas discharge chamber 8 is connected by a pipe 13 with the gas space in the tank, as shown in Fig. 1, and by a suitable discharge pipe 14. These pipes leading from the tank may be led to various points for use as desired.

The head 5 is provided with a central stuffing box and bearing portion comprising a bearing 15 having a seat 16 toward the inside of the tank. A suitable enlarged opening 17 in the stuffing box and bearing portion forms a suitable space for packing 18. A suitable gland ring 19 enters this space and this gland ring is held in place by a gland nut 20. Extending through this stuffing box and through the bearing 15 is a shaft 21 having a head 23 thereon provided with a plug portion adapted to engage in the seat 16, and a squared socket 24 for receiving a squared end 25 of the agitator shaft 26 which is mounted in the bearing 3 at the opposite end of the tank. The outer end of the shaft 21 is threaded at 27 and receives a nut 28. The extreme outer end of the shaft is provided with a suitable handle 29 or other agitating means.

The arrangement of the parts is such that when the nut 28 is loose upon the shaft 21, the shaft may be rotated freely and the proper agitation take place, the stuffing box preventing any leakage during the operation. When the agitating operation is finished, then the nut 28 is drawn up tightly against the gland nut 20, causing the shaft 21 to be drawn outward and the plug portion 23 to be drawn tightly against the seat 16 positively preventing any leakage from the tank to the stuffing box.

This device is utilized in fire extinguishers where it is desirable to maintain a pressure for a long period of time without any considerable loss. The arrangement however is adaptable to any construction wherein liquid

or gas is to be held under pressure and there is a movable member such as an agitator shaft entering the tank.

Having described my invention, I claim:

1. In an agitator tank construction, a tank, an agitator movable therein, a combined bearing and stuffing box mounted in said tank, an operating member extending through said stuffing box and operatively connected with the agitator, a plug on said operating member, and means on said operating member and external to the tank for positively seating said plug to prevent leakage about the operating member.
2. In an agitator tank construction, a tank, an agitator movable therein, a combined bearing and stuffing box mounted in said tank, an operating member extending through said stuffing box and operatively connected with the agitator, a plug on said operating member, and a nut threaded onto the operating member for positively seating the plug against the bearing and stuffing box for preventing leakage about the agitator member.
3. In an agitator tank construction, a tank, an agitator mounted therein, a combined bearing and stuffing box structure mounted in said tank, an operating shaft extending through said bearing and stuffing box structure, a driving head integral with

said shaft and having a driving connection with the agitator, said head having a portion adapted to seat against the bearing and 35 stuffing box structure, and means exterior to the tank for moving the operating shaft endwise to bring about the seating of the head thereon against the combined bearing and stuffing box structure.

4. In an agitator tank structure, a tank, an agitator shaft mounted in bearings in said tank and having a squared end portion, agitator blades mounted upon said shaft, a combined bearing and stuffing box 45 mounted in said tank, an operating shaft extending through said combined bearing and stuffing box, a head upon said shaft having a squared opening for receiving loosely the squared end of the agitator shaft, said head 50 having a portion adapted to seat against the combined bearing and stuffing box, and a nut threaded on to said shaft and outside of the tank for moving the same endwise to seat the head thereon against the combined bearing and stuffing box and thereby prevent leakage about the operating shaft.

In testimony whereof I affix my signature in presence of two witnesses as follows:

MAURICE N. CONNOR.
